ENCLOSED CIRCUIT INTERRUPTER

Lawrence Pierce, Pittsburgh, Pa., assignor to Westinghouse Electric & Manufacturing Company, East Pittsburgh, Pa., a corporation of Pennsylvania

Application July 20, 1940, Serial No. 346,530

20 Claims. (Cl. 200—44)

The invention relates to electrical switches or circuit breakers mounted in metal casings, and more particularly to devices for operating and locking such switches or circuit breakers.

The usual type of enclosed switch or circuit breaker has some form of lugs provided with holes for receiving padlocks to lock the operating handle in the "off" position. The constructions, however, have the disadvantage that it is possible to insert a padlock when the switch is in a closed circuit position. Similarly, in the case of constructions having multiple holes or slots for receiving several padlocks, these holes can be lined up so that a padlock can be inserted when the switch is in closed position. This is a dangerous condition for the reason that a person, unfamiliar with electrical switches, who is directed to lock a switch "off" may hang a padlock with the switch in "on" position thinking that he has locked it "off." The same dangerous condition is present to an even greater extent where the switch or circuit breaker is of the type embodying a snap action mechanism, for in many of these types the operating handle must be moved through the major portion of its throw or almost to the full "off" position before the snap action mechanism passes overcenter and becomes effective to open the contacts. In such cases a person may even move the handle toward "off" position and insert a padlock without having opened the contacts.

The copending application of Gilbert Currie, Serial No. 212,874, filed June 10, 1938, and assigned to the assignee of the present invention, now Patent No. 2,263,760, dated November 25, 1941, discloses and claims an enclosed switch or circuit breaker embodying one form of locking device which obviates the above described dangerous condition by providing a handle assembly having provision for receiving several padlocks and arranged so that a padlock can be inserted only when the handle is in the full "off" position. The present invention is a further development of features of the above mentioned copending application, and covers a different construction of locking device which is simpler and less expensive to manufacture than that disclosed in the aforementioned application.

An object of the invention is the provision of an enclosed switch or circuit breaker embodying an improved handle locking device having provision for receiving several padlocks and constructed and arranged so that a padlock can be inserted only when the switch is "off."

Another object of the invention is the provi-

sion of an enclosed circuit interrupter having a snap acting mechanism and an operating handle with a locking device associated therewith having a plurality of holes or slots for receiving several padlocks and constructed and arranged so that a padlock can be inserted only when the contacts of the interrupter are in full "off" position and the handle is in "off" position.

Another object of the invention is the provision of an enclosed circuit interrupter with an improved handle locking device which is simple, comprising a minimum number of parts, and which is inexpensive to manufacture.

In accordance with the invention the enclosed circuit interrupter embodies a handle locking device comprising two nesting cups or cylinders, one rigid with the operating handle and the other non-rotatably secured to the enclosing casing so that they are disposed in concentric relation to the axis of rotation of the handle. Each cup is provided with a plurality of openings identical to the openings of the other for receiving the hasp of an ordinary padlock and located so that they exactly line up only when the operating handle is in "off" position. The angular spacing of the holes in each cup must be more than the total angular throw of the operating handle. This makes the holes such that when the handle is in any other position than an "off" position, the holes in one cup are always disposed opposite a solid section of the other cup and a lock cannot be inserted.

The novel features that are considered characteristic of the invention are set forth in particular in the appended claims. The invention itself, however, both as to structure and operation, together with additional objects and advantages thereof will be best understood from the following detailed description of several embodiments thereof when read in conjunction with the accompanying drawings in which:

Figure 1 is a plan view of an enclosed switch embodying the features of the invention, part of the cover being broken away to show the switch mechanism, the switch being in the "on" position.

Fig. 2 is a fragmentary sectional view taken substantially along the line II—II of Fig. 1 showing the snap action mechanism;

Fig. 3 is a fragmentary sectional view taken along the line III—III of Fig. 2 and looking in the direction of the arrows;

Fig. 4 is an exploded perspective view of the handle assembly;

Fig. 5 is a fragmentary side elevational view

showing the operating handle in the full "off" position and the relation of the locking holes;

Fig. 6 is a view similar to Fig. 5 showing the operating handle in the "on" position;

Fig. 7 is a fragmentary side elevational view 5 of a modification of the invention showing the handle in the full "off" position;

Fig. 8 is a view similar to Fig. 7 showing the handle in the "on" position;

Fig. 9 is a perspective view of a modified handle 10 construction, and

Fig. 10 is a fragmentary plan view of the casing showing a cover locking device which may be added if desired.

Referring to the drawings, the enclosure for 15 the switch comprises a sheet metal casing 11 having side, end and bottom walls, and having a cover 13 pivotally attached to one of the side walls by a pair of hinges 15, the cover being provided with a peripheral flange 17 which overlaps the edges of the side and end walls.

A multipole switch mechanism is mounted in the casing and comprises an insulating base 19 upon which is mounted a plurality of hinged jaws 21 and contact jaws 23 for receiving a plurality of switch blades 25 that are pivoted to the hinged jaws at 27. Each switch blade 25 and its hinge and contact jaws 21 and 23 constitute one pole of the switch. The contact jaws 23 are provided with terminals 29 and the hinge jaws with terminals 31. If desired, each pole of the switch may be provided with a fuse 33 mounted in alignment with its corresponding switch blade and electrically connected in series therewith.

The switch blades 25 are of the knife blade type and are adapted to be simultaneously actuated by means of a bail 35 which constitutes a crank that is pivoted at its opposite ends to the side walls of the casing 11. Each switch 40 blade is mechanically connected to the bail or crank 35, and insulated therefrom, by means of a hook-shaped clamp 37 of insulating material. One end of the crank 35 is rotatably mounted in a bearing 39 on one of the side walls of the casing 11 and the opposite end of the crank is rotatably mounted in a tubular bushing or bearing 41 (Fig. 3) which is mounted on the opposite side wall of the casing in alignment with the bearing 39.

A snap action mechanism indicated generally at 43 is associated with the crank or bail 35 adjacent one end thereof for causing the switch blades to be actuated to open and to closed circuit positions with a snap action when the switch is operated. The snap action mechanism comprises an actuating member 45 rotatably mounted on the bushing 41, and a pair of oppositely disposed overcenter spring units 47 which engage the rotatable actuator 45 at 50 diametrically opposite points.

The actuating member 45 (Figs. 2, 3 and 4) comprises a pair of spaced plates 49 and 51 rigidly secured together in slightly spaced relation by a pair of spacer pins 53, the ends of which are riveted over against the plates. The plates 49 and 51 are provided with a central opening in which is mounted a bearing sleeve 55 by means of which the actuating member 45 is rotatably mounted on the bushing 41. The 70 actuating member 45 has a lost motion connection with the crank 35 and for this purpose the inner plate 49 of the member 45 is provided with an angular extension 57 having a pair of spaced arms 59 adapted to engage the opposite 75

sides of the bent portion of the crank 35. The actuating member 45 is, in turn, adapted to be manually oscillated by means of an operating handle mounted on the outside of the casing, which will hereinafter be described. The operating handle is provided with a driving element which extends through a slot in the side of the casing and engages a slot 61 formed in the plate 51 of the actuating member 45. The slot 61 provides a lost motion connection between the operating handle and the actuating member 45.

Each overcenter spring unit 47 comprises an actuating fork 63 and a coil spring 65 which is mounted on the arm of the fork 63 and disposed in compression between the head of the fork and an angle-shaped guide bracket 67. The guide bracket 67 is pivotally mounted on the side wall of the casing 11 by means of a pivot stud 69, and the angularly projecting end of the bracket 67 is provided with an opening through which the outer end of the fork arm extends. The heads 71 of the actuating forks 63 pivotally engage the pins 53 of the actuating member 45 between the plates 49 and 51.

When the actuating member 45 is rotated in either direction by the operating handle, the springs 65 are compressed during the first portion of the movement and as soon as the connecting pins 53 cross the line joining the fixed pivots 69 of the springs, the line of action of the springs is shifted, so that the springs act to continue the movement of the actuating member from this point on with a snap action. The arms 59 of the actuating member 45 are preferably spaced apart a sufficient distance so that they engage and begin to move the crank 35 approximately at the point when the springs 65 pass overcenter.

An interlock is provided for preventing opening of the cover except when the switch is in "off" position and also for preventing closing of the switch when the cover is open. This interlock comprises an interlock lever 73 (Fig. 2) having an offset inner end 75 which pivots in an opening 77 provided in the side wall of the casing 11. The interlock lever 73 is biased in a clockwise direction by means of a compression spring 79 interposed between the projection 81 of the interlock lever and the bottom wall of the casing 11. The outer end 83 of the interlock lever operates with a spring pressed latch 85 mounted on the inside of the cover 13 of the casing. The interlock lever 73 is operated in accordance with the position of the operating handle of the switch by means of a cam plate 87 which moves with the operating handle and which is rotatably mounted on the bushing 41 between the actuating member 45 and the side wall of the casing 11. The cam plate 87 is connected for movement with the operating handle by means of a slot 89 therein which engages the driving element of the operating handle. The interlock lever 73 is provided with an arcuate edge 91 which rides on the periphery of the cam plate 87 and the cam plate is provided with a notch 93 which is positioned opposite the arcuate edge 91 of the interlock lever when the operating handle is in the "off" position, so as to permit opening of the cover when the operating handle is in "off" position. The cover when in closed position bears against the end of the interlock lever and prevents the edge 91 from dropping into the notch 93. As the cover is opened the interlock lever is rotated a small distance in a clockwise

direction by the spring 78 so that the arcuate edge 91 seats in the notch 93 of the cam plate 87, and the free end 83 clears the latch 85. In this position the interlock lever 73 functions to prevent closing of the switch as long as the cover is open.

The switch mechanism described above is similar to that disclosed in the copending application of J. W. Samzelius, Serial No. 346,528, filed July 20, 1940, and assigned to the assignee of the present invention, now Patent No. 2,276,006, granted March 10, 1942.

The operating handle 94 of the switch comprises an operating lever 95, a driving element 97, and a cup-shaped locking element 99 all secured to rotate as a rigid unit on the bushing 41 at the outside of the casing 11. The cup-shaped locking element 99 cooperates with a fixed locking cup 101 secured to the wall of the casing to provide a means for locking the switch and handle in "off" position, as will be described hereinafter.

The fixed locking cup 101 has a centrally disposed tubular sleeve 103 which fits snugly in an opening provided therefor in the side wall of the casing 11, and the bushing 41 extends through the sleeve 103 and is provided with a shoulder 105 which bears against the locking cup 101 to retain it in mounted position. A cotter key 107 engages an annular slot on the inner end of the bushing 41 to maintain the actuating member 45 and the cam plate 87 in mounted position on the bushing 41, and also cooperates with the shoulder 105 of the bushing to maintain the locking cup 101 and the bushing in assembled position on the casing. The locking cup 101 is provided with an integral projection 109 which extends through an opening in the wall of the casing, and this projection cooperates with a pair of shoulders 111 and 113 formed on the actuating member 45 to limit movement of the actuating member 45 in both directions.

The offset inner end of the handle lever 95, the driving element 97, and the central portion of the cup-shaped locking element 99 are each provided with a circular opening by means of which these elements are rotatably mounted on the outer portion of the bushing 41. The handle lever 95 extends through an opening 115 provided therefor in the peripheral flange of the cup-shaped locking element and this opening fits the lever snugly so that the handle lever 95 and cup-shaped locking element 99 are rigidly coupled for rotation together.

The driving element 97 is mounted on the bushing 41 between the inner end of the handle lever 95 and the cup-shaped locking element 99 and is provided with an angularly bent driving projection 117 which fits snugly in a notch 98 (Figs. 5 and 6) provided therefor in the inner end of the handle lever 95 so that the driving element is thereby rigidly coupled to the handle lever for rotation therewith. The driving projection 117 extends through aligned arcuate slots 119 and 121 formed in the fixed locking cup and in the wall of the casing 11 and also passes through the close fitting slot 89 of the rotatable cam plate 87. The inner end of the driving projection engages in the arcuate slot 61 of the snap-acting actuating member 45. The parts 95, 97 and 99 of the switch operating handle are retained in mounted position on the bushing 41 by riveting over the outer end of the bushing 41 adjacent the cup-shaped locking element 99 as shown in Fig. 3.

The operation of the switch is briefly as follows: The switch mechanism and operating handle are shown in the "on" or closed-circuit position in Figs. 1, 2, 3 and 6. To operate the switch to the "off" or open-circuit position, the operating handle 94 is manually moved downwardly, that is to say, in a counterclockwise direction to the "off" position shown in Fig. 5. The driving element 97 and the cup-shaped locking element 99 move as a rigid unit with the operating lever 95, and as soon as the lost motion provided by the slot 61 is taken up the driving element 97 moves the snap-acting actuating member 45 in a counterclockwise direction with the operating handle. The crank 35 and switch blades 25 however, remain in the "on" position during the first portion of the movement of the actuating member 45 until approximately the time that the overcenter spring units 47 pass overcenter. This is due to the lost motion connection between the crank 35 and the actuating member 45 provided by the spaced arms 59 of the actuating member. As soon as the overcenter spring units 47 pass overcenter, the actuating member 45 is moved with a snap action from this point on to the full "off" position where it is stopped by the shoulder 111 thereof engaging the stop projection 109. Approximately at the time the spring units 47 begin to pass overcenter the trailing arm 59 of the actuating member 45 engages the crank 35 so that this crank and the switch blades 25 are moved with a snap action to the full "off" position by the actuating member 45 and spring units 47. By reason of the slot 61 it is impossible to check the snap acting movement of the switch mechanism once this movement is started, since the actuating member is moved ahead of the handle by the overcenter springs as soon as they pass overcenter.

In operating the switch to the "on" position substantially the reverse operation takes place. The operating handle 94 is manually moved in a clockwise direction to the "on" position shown in Figs. 1, 2, 3 and 6. As soon as the spring units 47 have been moved overcenter, the force of the springs acts to move the actuating member 45 and the switch blades 25 to the "on" position with a snap action.

A pair of stops 123 on a bracket 125 secured to a side wall of the casing are adapted to be engaged by the crank 35 in the "on" and "off" positions of the crank to take up the shock of the moving parts and to limit the movement of the crank.

In accordance with the invention, the fixed locking cup 101 and the cup-shaped locking element 99 cooperate to provide a means for locking the switch and operating handle in the "off" position. For this purpose the fixed locking element 101 has a cylindrical flange 127 disposed concentric to the axis of rotation of the operating handle and provided with a plurality of spaced slots or openings 129, each of sufficient size to receive the hasp of a padlock. The central portion of the cup-shaped locking element 99 is depressed so as to provide a circular rim or flange 131 which has a U-shaped cross section as shown in Fig. 3. The cup-shaped locking element 99 is disposed in nesting relation with the fixed locking cup 101 so that the periphery of the flange 131 of the cup-shaped locking element 99 overlies the flange 127 of the fixed locking cup 101. The flange 131 of the cup-shaped locking element 99 is provided with a plurality of spaced openings 133, each of just sufficient

size to receive the hasp of a padlock. The openings 133 of the cup-shaped locking element 99 and the opening 129 of the fixed locking element 101 are equally spaced and arranged so that they exactly line up when the opening handle 94 is in the full "off" position such that the hasp of a padlock can be inserted through each pair of lined up openings 129 and 133 to lock the operating handle in the full "off" position. The angular spacing of the openings 129 and the openings 133 of each cup is made more than the total angular throw of the operating handle 94 so that when the operating handle is in any other position than the "off" position the openings of one cup are disposed opposite a solid section of the other cup and a padlock cannot be inserted. In the embodiment of the invention illustrated in Figs. 1 to 6, three openings are provided in each locking element and these openings are angularly spaced 120° apart, the angular throw of the operating handle being less than 120°. The arrangement permits the use of as many padlocks as the complete circle of 360° divided by slightly more than the angular throw of the operating handle permits, and still at no time does any opening line up with any other opening except in the "off" position of the operating handle.

Fig. 5 shows the operating handle 94 in the full "off" position. In this position the openings 133 of the cup-shaped locking element 99 are exactly lined up with the openings 129 of the fixed locking cup 101, so that one or more padlocks can be inserted to lock the switch in "off" position. When the operating handle 94 is in any other position than the full "off" position, a padlock cannot be inserted since the openings of one cup are disposed opposite solid section of the other cup. Fig. 6 shows the operating handle in the "on" position, and in this position each lock opening is disposed opposite a solid section of the other locking cup so that it is impossible to insert a padlock.

A modification of the invention is illustrated in Figs. 7 and 8. In Figs. 7 and 8 the same reference characters with a prime mark are used to designate the elements which correspond to those of the original embodiment. In this modification the cup-shaped locking element 99' is provided with openings 135 and 137, and the fixed locking cup 101' is provided with identical openings 139 and 141. The openings 135 and 139 are of just sufficient size to receive the hasp of a single padlock. The openings 137 and 141, however, are made of sufficient size to receive the hasps of two padlocks. Thus the switch can be locked in the "off" position by the insertion of one, two or three padlocks. The openings of the cup-shaped locking element 99' and the openings of the fixed locking cup 101' are spaced apart a greater distance than the throw of the operating handle 94' and arranged so that they line up exactly when the handle is in the full "off" position. The throw of the operating handle 94' in this modification is made slightly greater in an opening direction than the throw of the operating handle 94 of the original embodiment, and the arrangement is such that a padlock cannot be inserted except when the handle is in an "off" position such that the switch mechanism is in the full "off" position. Although the openings 137 and 141 may be partially lined up a sufficient amount when the handle is near the full "off" position to permit the insertion of a padlock therethrough, the con-

struction is such that the switch mechanism will be in the full "off" position whenever these openings are lined up a sufficient amount to permit the insertion of a padlock. Thus it is impossible to insert a padlock except when the switch mechanism is in the full "off" position.

A further modification of the invention is shown in Fig. 9. In this modification the operating handle 145 of the switch is formed as a single integral element having a handle lever portion 147 and an integral cup-shaped locking portion 149 having a plurality of spaced padlock receiving openings 151 arranged in the same manner as the lock openings of the original embodiment shown in Figs. 1 through 6. The operating handle 145 has a driving element 153 rigidly secured thereto for operating the switch mechanism. The remaining construction of the switch mechanism and the fixed locking cup on the casing are identical to the embodiments shown in Figs. 1 through 6.

It will be noted that in all of the embodiments of the invention previously described a padlock cannot be hung or inserted anywhere on the casing without locking the switch "off." This makes the enclosure switch absolutely safe. It is, therefore, desirable not to have any other place on the casing where a padlock can be hung except in the handle locking device. However, in those cases where it is desired to lock the cover closed to prevent unauthorized entry into the casing a cover locking device may be added as shown in Fig. 10. Referring to Fig. 10 the cover locking device comprises a latch 157 which is pivoted at 158 to the side wall of the casing 11 and has a latch nose 159 adapted to extend through a slot 161 in the cover 13. The latch is biased by a spring 163 to latching position in which the latch nose 159 engages over one end edge of the slot 161. An ear 165 is secured to the cover 13, and this ear is provided with an opening 167 which aligns with an opening 169 in the projecting end of the latch 157 when the latch is in latching position. The cover 13 may be locked closed by inserting a padlock through the openings 167 and 169.

If desired a knockout may be provided in the flange of either the fixed locking element or the movable locking element in any of the previously described embodiments, such knockout being disposed to line up with one of the openings of the other locking element when the operating handle is in "on" position so that the switch may be locked by a padlock in the "on" position after removing the knockout. Such a knockout is indicated by the dotted line at 130 in Fig. 4.

For special applications a switch may be required which can be locked only in the "on" position by more than one padlock, instead of in the "off" position as previously described. This may be accomplished by the same elements of the invention previously described except that in such instance the locking holes of the fixed and movable locking elements would be disposed so as to exactly line up only when the operating handle is in "on" position.

The invention provides an enclosed circuit interrupter embodying an improved handle locking construction such that a padlock can be inserted only when the switch is in the full "off" position and such that several padlocks can be used to lock the switch "off." The construction is absolutely safe since it is impossible to hang

or insert a padlock except when the switch is in the full "off" position.

While the invention has been disclosed in accordance with the provisions of the patent statutes, it is to be understood that various changes in the structural details thereof may be made without departing from some of the essential features of the invention. It is desired, therefore, that the appended claims shall be accorded the broadest reasonable construction consistent with their language and the prior art.

I claim as my invention:

1. An enclosed circuit interrupter comprising an enclosing casing, circuit interrupter mechanism mounted in said casing, a movable operating handle on said casing for operating said interrupter, and handle locking means comprising a fixed locking element on said casing and a cooperating locking element movable with said handle having provision for receiving one or more locks to lock said interrupter in "off" position and disposed so that a lock cannot be inserted in either locking element except when the interrupter is in full "off" position.

2. An enclosed circuit interrupter comprising an enclosing casing, circuit interrupter mechanism in said casing, an operating handle on said casing movable to "on" and "off" positions for operating said interrupter, and handle locking means comprising a fixed locking element on said casing and a cooperating locking element movable with said handle having openings for receiving a padlock to lock said handle "off" and said openings being disposed so that a padlock cannot be inserted through any opening except when said handle is in a position such that the interrupter is in full "off" position.

3. An enclosed circuit interrupter comprising an enclosing casing, a circuit interrupter in said casing, an operating handle on said casing movable to "on" and "off" positions for operating said interrupter to "on" and "off" positions, handle locking means comprising a fixed locking element on said casing and a cooperating locking element movable with said handle, said locking elements having openings for receiving several locks to lock said interrupter "off," said openings being disposed so that a lock cannot be inserted through any opening except when the interrupter and handle are in "off" position.

4. An enclosed circuit interrupter comprising an enclosing casing, a circuit interrupter in said casing, an operating handle on said casing movable to "on" and "off" positions for operating the interrupter to "on" and "off" positions, handle locking means comprising a fixed locking element on said casing and a cooperating locking element movable with said handle, said locking elements having a plurality of cooperating openings for receiving several padlocks to lock said interrupter "off," said openings being disposed so that all of the openings of each element lie opposite solid sections of the other for all positions of the handle except where the handle is in a position such that the interrupter is in "off" position.

5. An enclosed circuit interrupter comprising an enclosing casing, a circuit interrupter in said casing, an operating handle on said casing movable to "on" and "off" positions for operating said interrupter to "on" and "off" positions, means for locking said interrupter "off" comprising a fixed locking element on said casing and a cooperating locking element movable with said handle, said locking elements each having

10 a plurality of spaced openings disposed to line up when said handle is in "off" position for receiving a plurality of locks, any one lock when inserted through a lined up pair of said openings of said locking elements effecting locking of the interrupter in "off" position, said locking elements and said openings being disposed so that a lock cannot be inserted through any one of said openings except when said handle is in a position such that the interrupter is in "off" position.

15 6. An enclosed circuit interrupter comprising an enclosing casing, a circuit interrupter in said casing, an operating handle on said casing movable to "on" and "off" positions for operating said interrupter to "on" and "off" positions, said handle having a locking portion which cooperates with a fixed locking means on said casing, said locking portion and said locking means each having a plurality of spaced openings disposed to line up when said handle is in "off" position for receiving a plurality of padlocks, any one padlock when inserted through a pair of lined up openings effecting locking of said handle and interrupter in "off" position, said openings being disposed so that a padlock cannot be inserted in any of said openings except when said handle is in a position such that the interrupter is in "off" position.

20 7. An enclosed circuit breaker comprising an enclosing casing, a circuit interrupter in said casing, an operating handle rotatably mounted on said casing and movable to "on" and "off" positions for operating said interrupter to "on" and "off" positions, a fixed locking element on said casing having a substantially cylindrical flange disposed concentric to the axis of rotation of said handle, said handle having a substantially cylindrical flange disposed in nesting relation with the flange of said locking element, 25 said flanges each having a plurality of spaced openings which line up when said handle is in "off" position for receiving a plurality of padlocks to lock said interrupter "off," said openings being disposed so that a padlock cannot be inserted in any of said openings except when said handle is in a position such that the interrupter is in "off" position.

30 8. An enclosed circuit interrupter comprising an enclosing casing, a circuit interrupter mounted in said casing, an operating handle on said casing movable to "on" and "off" positions for operating said interrupter to "on" and "off" positions, locking means for locking said interrupter "off" comprising a fixed locking portion on said casing and a cooperating locking portion movable with said handle, said locking portions each having a plurality of openings spaced apart a greater distance than the throw of said handle so that the openings line up only when said handle is in "off" position for receiving a plurality of locks to lock the handle and interrupter "off," said openings being disposed so that a lock cannot be inserted in any opening except when said handle is in "off" position.

35 9. An enclosed circuit interrupter comprising an enclosing casing, a circuit interrupter in said casing, a rotatable operating handle on said casing movable to "on" and "off" positions for operating said interrupter to "on" and "off" positions, a fixed locking element on said casing having a substantially cylindrical flange disposed concentric to the axis of rotation of said handle, said handle having a substantially cylindrical locking flange disposed in nesting relation with the flange of said fixed locking element, said flanges each having a plurality of openings spaced apart a greater angu-

lar distance than the angular throw of said handle so that they line up only when said handle is in "off" position for receiving a plurality of padlocks to lock said handle and interrupter "off."

10. In an enclosed circuit interrupter, an enclosing casing, circuit interrupter mechanism mounted in said casing including relatively movable contacts and a snap-acting actuating mechanism therefor, an operating handle on said casing movable to "on" and "off" positions for operating said snap-acting mechanism to actuate said contacts, said handle being movable through a considerable portion of its throw before said snap-acting mechanism actuates said contacts, locking means comprising a fixed locking element on said casing and a cooperating locking element movable with said handle, said elements each having a plurality of openings which line up when said handle is in "off" position for receiving a plurality of padlocks to lock said handle and interrupter "off," said openings being disposed so that a padlock can be inserted only when said handle is in a position such that the contacts of the interrupter are in "off" position.

11. An enclosed circuit interrupter comprising an enclosing casing, circuit interrupter mechanism in said casing including relatively movable contacts and a snap-action mechanism therefor, a rotatable operating handle on said casing movable to "on" and "off" positions for operating said snap action mechanism to actuate said interrupter contacts to "on" and "off" positions, said handle being movable through a considerable portion of its travel before said snap-action mechanism actuates said interrupter contacts, a fixed locking element on said casing having a substantially cylindrical flange concentric with the axis of rotation of said handle, said handle having a substantially cylindrical locking flange disposed in nesting relation with the flange of said fixed locking element, said flanges each having a plurality of openings which line up when said handle is in an "off" position for receiving a plurality of locks to lock said interrupter "off," said openings being disposed so that a lock can be inserted only when said handle is in an "off" position such that the interrupter contacts are in "off" position.

12. An enclosed circuit interrupter comprising an enclosing casing, a circuit interrupter in said casing including relatively movable contacts and a snap-acting mechanism therefor comprising a rotatable member for moving said contacts and spring means for causing snap-acting movement of said rotatable member, a rotatable operating handle on said casing movable to "on" and "off" positions for moving said rotatable member to actuate said contacts to "on" and "off" positions, a fixed locking element on said casing having a substantially cylindrical flange concentric with the axis of rotation of said handle, said handle having a substantially cylindrical locking flange disposed in nesting relation with the flange of said locking element, said flanges each having a plurality of openings which line up when said handle is in an "off" position for receiving a plurality of padlocks to lock the interrupter "off," said openings being disposed so that a padlock can be inserted only when said handle is in a position such that the interrupter contacts are in "off" position.

13. An enclosed circuit interrupter comprising an enclosing casing, a circuit interrupter in said casing, a rotatable operating handle on said casing movable to "on" and "off" positions for operating said interrupter to "on" and "off" positions, 75

a fixed locking element on said casing having a substantially cylindrical flange concentric with the axis of rotation of said handle, said handle having a substantially cylindrical locking flange disposed in nesting relation with the flange of said locking element, said flanges each having three spaced openings which line up with the openings of the other when said handle is in "off" position for receiving padlocks to lock the interrupter "off," the openings of each flange being spaced apart a greater distance than the throw of said handle so that a padlock can be inserted only when said handle is in "off" position.

14. An enclosed circuit interrupter comprising an enclosing casing, a circuit interrupter in said casing, a rotatable operating handle on said casing movable to "on" and "off" positions for operating said interrupter to "on" and "off" positions, a fixed locking element on said casing having a substantially cylindrical flange concentric with the axis of rotation of said handle, said handle having a substantially cylindrical locking flange disposed in nesting relation with the flange of said locking element, said flanges each having two openings which line up when said handle is in "off" position for receiving padlocks to lock the interrupter "off," the openings of each flange being spaced apart a greater distance than the throw of said handle so that a padlock can be inserted only when the handle is in a position such that the interrupter is "off," and at least one of the openings of each flange being of sufficient size to receive the hasps of two padlocks.

15. An enclosed circuit interrupter comprising an enclosing casing, a circuit interrupter in said casing, an operating handle on said casing movable to full "on" and "off" operating positions for operating said interrupter to "on" and "off" positions, handle locking means comprising a fixed locking element on said casing and a co-operating locking element movable with said handle, said locking elements each having a plurality of locking openings which line up only when said handle is in one of said aforementioned operating positions for receiving several padlocks to lock said switch and handle in said one operating position, said openings being disposed so that a padlock can be inserted only when said handle is in said one operating position.

16. In an enclosed circuit interrupter, an enclosing casing, a circuit interrupter in said casing having relatively movable contacts, an operating handle on said casing movable to "on" and "off" positions for operating said interrupter to "on" and "off" positions, a snap-acting mechanism in said casing for causing said contacts to be actuated with a snap-action comprising a rotatable member for moving said contacts, said rotatable member having a lost motion connection with said handle and being movable by said handle, spring means engaging said rotatable member for imparting snap-acting movement to said rotatable member after said member has been moved a predetermined amount by said handle, handle locking means comprising a fixed locking element on said casing and a cooperating locking element movable with said handle, said locking elements each having a plurality of spaced openings which line up with the openings of the other when the handle is in "off" position for receiving a plurality of padlocks to lock the interrupter "off," said openings being disposed so that a padlock can be inserted only when the

handle is in "off" position such that the interrupter contacts are in full "off" position.

17. In an enclosed circuit interrupter, an enclosing casing, a circuit interrupter in said casing having relatively movable contacts, a rotatable operating handle on said casing movable "on" and "off" positions for operating said interrupter to "on" and "off" positions, a snap-acting mechanism in said casing for causing said contacts to be actuated with a snap-action, comprising a rotatable member rotatable about the same axis as said handle for moving said contacts, said rotatable member having a slot in which an element of said handle projects to provide a lost motion connection between said rotatable member and said handle, said handle being operable to move said rotatable member, spring means engaging said rotatable member for imparting snap-acting movement to said rotatable member when said member has been rotated a predetermined amount by said handle, handle locking means comprising a fixed locking element on said casing having a substantially cylindrical flange concentric with the axis of rotation of said handle and disposed in nesting relation with a substantially cylindrical locking flange of said handle, said flanges each having a plurality of spaced openings which line up when said handle is in "off" position for receiving a plurality of padlocks to lock said interrupter "off," the openings of each flange being spaced apart a greater distance than the throw of said handle so that a padlock can be inserted only when the handle is in "off" position such that the interrupter is in full "off" position.

18. An enclosed circuit interrupter comprising an enclosing casing, a circuit interrupter in said casing, a rotatable operating handle on said casing movable to "on" and "off" positions for operating the interrupter to "on" and "off" positions, locking means comprising a locking element fixedly secured to said casing and having a substantially cylindrical flange concentric with the axis of rotation of said handle, said handle having a cooperating cup-shaped portion having a substantially cylindrical flange extending inwardly toward the casing and enclosing the flange of the locking element on said casing, said flanges each having an opening, the openings being disposed to line up when the handle is in "off" position for receiving a padlock to lock the interrupter "off."

19. An enclosed circuit interrupter comprising

- an enclosing casing, circuit interrupter mechanism in said casing, a rotatable operating handle on said casing movable to "on" and "off" positions for operating the interrupter to "on" and "off" positions, snap-acting mechanism between said circuit interrupter mechanism and said handle for actuating said interrupter with a snap action when said handle has been moved a predetermined amount from one operating position towards the other, and locking means comprising a cup-shaped locking element fixedly secured to said casing and having a substantially cylindrical flange concentric with the axis of rotation of said handle, and a cooperating cup-shaped element on said handle having a substantial cylindrical flange concentrically enclosing the flange of the cup-shaped element on the casing, said elements each having a plurality of openings which line up when the operating handle is in "off" position for receiving a plurality of padlocks to lock the interrupter "off."
20. An enclosed circuit interrupter comprising an enclosing casing, circuit interrupter mechanism in said casing having relatively movable contacts, a rotatable operating handle on said casing movable to "on" and "off" positions for operating said interrupter to "on" and "off" positions, snap-acting mechanism in said casing for causing said interrupter to be actuated with a snap action, said snap-acting means comprising a rotatable member rotatable about the same axis as said handle for actuating the interrupter, said rotatable member having spaced portions engageable by an element movable with said handle to provide a lost-motion connection between said rotatable member and said handle, said handle being operable to move said rotatable member, spring means engaging said rotatable member for imparting snap-acting movement to said rotatable member when said rotatable member has been rotated a predetermined amount by said handle, locking means comprising a cup-shaped locking element secured to said casing and having a substantially cylindrical flange concentric with the axis of rotation of said handle and disposed in nesting relation within a cooperating substantially cylindrical flange of said handle, said flanges each having a plurality of spaced openings which line up when said handle is in "off" position for receiving a plurality of padlocks to lock said interrupter "off."
